CLASSIFYING MACHINE

Robert K. Barry, Muscatine, Iowa, assignor to
 Barry Company, Muscatine, Iowa, a corpora-
 tion of Iowa

Application March 30, 1942, Serial No. 436,887

2 Claims. (Cl. 209—107)

This invention is a novel machine for classifying, sorting, calibrating, or separating articles such as armor piercing bullets for cartridges, steel ball bearing balls, wrist pins, or the like, which articles are allowed a small tolerance in diameter or size usually measured in thousandths of an inch; and the principal object thereof is to provide a machine consisting essentially of a pair of relatively long oppositely rotating and slightly diverging rolls, mounted in a frame in such manner as to be adjustable horizontally and vertically, said rolls being normally inclined to the horizontal. The articles to be classified or sorted are discharged from a hopper disposed at the higher end of the rolls, said articles falling between the rolls at their more closely adjacent upper ends, and moving downwardly while supported between the oppositely rotating and diverging rolls until the spacing of the rolls permits same to drop into one of a series of receiving pens disposed beneath the rolls. By such construction the slight angularity between the rolls throughout their entire length provides a very slight variation in the space between the rolls for each inch of travel of the articles in their downwardly inclined path between the rolls, the difference in the spacing at the opposite ends of the rolls embracing the entire or total permitted tolerance for the size or diameter of the articles for which the machine is set, whereby the classification of the articles can be based upon very close tolerances. For instance, 30 caliber armor piercing bullets are permitted a total tolerance of .001", and by proper adjustment of the rolls at each end of the machine, all bullets either larger or smaller than the above tolerance would be rejected. The rolls however would be spaced differently for classifying different caliber bullets or articles.

Another object of the invention is to provide a hopper for feeding the articles to the rolls, the articles being fed by gravity onto a vibrating and inclined pan disposed below the hopper discharge, the vibration of the pan spreading and feeding the articles in proper sequence or relation to and between the inclined revolving rolls at their upper ends, between which rolls the articles travel downwardly until they drop through into one of the receiving pens.

A further object of the invention is to provide a novel means for mounting the rolls in the frame of the machine so that the vertical inclination of the pair of rolls, and the spacing between the pair of rolls, may be readily adjusted.

Other minor objects of the invention will be hereinafter set forth.

I will explain the invention with reference to the accompanying drawings, which illustrate one practical embodiment thereof, to enable others familiar with the art to adopt and use the same; and will summarize in the claims, the novel fea-

tures of construction, and novel combination of parts, for which protection is desired.

In said drawings:

Fig. 1 is a perspective view of my novel machine showing the arrangement of the rolls, hopper, and receiving pens; and showing the belt drive for rotating the rolls in opposite directions.

Fig. 2 is a top plan view thereof showing the hopper partly broken away.

10 Fig. 3 is a transverse section on the line 3—3, Fig. 2, taken through the discharge end of the frame, showing the sliding sub-frame for adjusting the vertical inclination of the pair of rolls; and showing the means for adjusting the spacing between the rolls at the discharge end of the machine.

Fig. 4 is a transverse section through the hopper and vibrating pan which feeds the articles to and between the rolls.

20 Fig. 5 is a plan view of the horizontally adjustable roll, detached, showing the bearing yokes and trunnions, and the roll bearings at each end of the roll.

Fig. 6 is a vertical section through the frame 25 at the feeding end of the machine, showing the means for adjusting the spacing between the rolls at said end.

The machine preferably comprises an open vertical frame 1 at the feeding end of the machine, and an open vertical frame 2 at the discharge end of the machine, said frames 1 and 2 being connected together by horizontal rods 3 transfixing the upper and lower corners of the frames 1 and 2, said rods 3 being provided with

30 heads or nuts 3a—3b respectively engaging opposite faces of the frames to maintain same in spaced relation. Preferably frames 1 and 2 are open and include side members, top, and bottom members respectively. Frame 1 at the feeding

40 end of the machine is provided with an intermediate horizontal member 1a (Fig. 1) disposed between the top and bottom thereof, and an inclined platform 4 is disposed between said horizontal member 1a and the bottom member of the frame 2, as shown in Fig. 1, said platform 4 being adapted to hold a series of closely spaced receiving pens 4a, fourteen such pens being shown (Fig. 1) into which the classified or sorted articles are dropped, as hereinafter explained.

50 Above platform 4 are a pair of spaced rolls 6 and 7 which are inclined downwardly from the feeding end of the machine to the discharge end, said pair of rolls 6 and 7 being adjustable vertically, and roll 6 being adjustable towards or from roll 7, as hereinafter described. Preferably each of rolls 6 and 7 are approximately 5½ inches in diameter and are about 6 feet long, and are preferably made of cold drawn seamless steel tubing about ¾ inch thick, each roll being turned and ground smooth and true. The ends 55 of rolls 6 and 7 receive plugs provided with stub

shafts which are journaled in self-aligning roll bearings, which latter are readily adjustable to control the spacing between the two rolls while permitting adjustment of the vertical inclination of the pair of rolls.

Roll 7 is adjustable vertically only, and the stub shaft 8 (Fig. 6) at the upper end of said roll carries a roll bearing 9 around which is a bearing yoke 10 having a horizontally disposed arm 11 rotatably mounted in a horizontal bore 1b in the side of the frame 1, said arm 11 being maintained against axial movement in bore 1b while being rotatable therein. The lower end of the roll 7 is journaled in a vertical sliding frame 12 (Fig. 3) in the frame 2.

As shown in Fig. 3, within frame 2 at the discharge end of the machine is a sliding frame 12 vertically movably mounted therein, said sliding frame being open and comprising side, top and bottom members, respectively. In the top member of sliding frame 12 is a threaded bore 12a receiving an adjusting screw 13 having threads engaging the threaded bore 12a, said screw 13 passing upwardly through a bore 2a in the top member of frame 2 and being rotatable therein. Screw 13 carries on its upper end a hand-wheel 14, the hub of which contacts the top of frame 2, whereby rotation of hand-wheel 14 will raise and lower the sliding frame 12 within the frame 2.

The lower stub shaft 8 of the roll 7 (Fig. 3) also carries a roll bearing 9 journaled within a bearing yoke 10 provided with a horizontally disposed arm 11 rotatably mounted in a bore 12b in the side of the sliding frame 12, the arm 11 being held against axial movement in said bore 12b but being rotatable therein. By the above construction, while the upper bearing yoke 10 of roll 7 is carried by the frame 1, and the lower bearing yoke 10 is carried by the sliding frame 12 of the frame 2, it is obvious that as the sliding frame 12 is raised or lowered by turning hand-wheel 14 the roll bearings 9 at the upper and lower ends of roll 7 will be maintained in proper alignment for any vertical inclination to which roll 7 is adjusted, since the arms 11 of the bearing yokes 10 at each end of said roll are each disposed horizontally and can rotate in their supports; and thus the vertical inclination of roll 7 may be readily adjusted merely by rotating hand-wheel 14 which raises or lowers sliding frame 12.

The other roll 6 is disposed in the same plane as the roll 7 for any adjustment of sliding frame 12, but the ends of roll 6 are adjustable towards or away from roll 7. As shown in Figs. 5 and 6, the upper stub shaft 8 of roll 6 is provided with a roll bearing 9 around which is an enlarged bearing yoke 15 spaced therefrom and provided with opposed vertically disposed bearing pivot pins 15a, which pins pass through the bearing yoke 15 and into the roll bearing 9 so as to permit the angularity of the roll 6 to vary from that of roll 7. Extending laterally from the bearing yoke 15 is a horizontal arm 16 entering a bore 1c in a boss 1d on the side of main frame 1, said arm 16 terminating within bore 1c and having a threaded bore 19 extending inwardly from its outer end. Within the bore 1c is mounted a sleeve 20 which is held against axial movement in said bore 1c in any desired manner, said sleeve 20 carrying a screw shaft 22 held from axial movement in said sleeve, and said shaft 22 carrying a hand-wheel 21 at its outer end beyond the frame 1. Screw shaft 22 enters the threaded bore 73

19 of arm 16, whereby rotation of the hand-wheel 21 will cause the arm 16 to move inwardly or outwardly, according to the direction of rotation of the hand-wheel, to adjust the bearing yoke 15 of roll 6 towards or from the roll 7 at the feeding end of the machine, the arm 16 being rotatable in said bore 1c.

The stub shaft 8 at the lower end of roll 6 (Fig. 3) is similarly provided with a roll bearing 9 supported in a bearing yoke 15 having vertically disposed and opposed bearing pivot pins 15a; and bearing yoke 15 has a horizontal arm 16 passing through a bore 12c in a boss 12d on the side of sliding frame 12, the outer end of the boss 12d passing through a vertical slot 2s in the side of frame 2, said boss 12d projecting beyond the side of frame 2 as shown in Fig. 1, and said slot 2s permitting the sliding frame 12 to be raised or lowered in frame 2. In the outer end of bore 12c of sliding frame 12 is a sleeve 25 which is held against axial movement in bore 12c, said sleeve 25 carrying a screw shaft 27 held against axial movement in said sleeve, said shaft 27 carrying a hand-wheel 26 at its outer end. Screw shaft 27 engages a threaded bore 28 in the end of arm 16 of the yoke, whereby rotation of hand-wheel 26 will adjust the lower bearing yoke 15 of roll 6 towards or from the roll 7 according to the direction of rotation of said hand-wheel.

By the above construction, as sliding frame 12 is raised or lowered, the arms 11 and 16 of the upper and lower bearing yokes 10 and 15 of the rolls 7 and 6 will merely rotate slightly in their respective horizontal bores in the sliding frame 12 and in the main frame 1, so that the bearings at each end of the rolls 7 and 6 will remain in proper alignment for any adjustment of the sliding frame 12, permitting the rolls to rotate freely without binding.

The horizontally adjustable roll 6 however may in addition be adjusted by rotation of hand-wheels 21 and/or 26 to shift the respective ends of the roll 6 towards or from the roll 7, the vertical bearing pivot pins 15a together with the horizontal rotatable arms 16 of the bearing yokes 15 permitting universal movement of the roll bearings 9 at the respective ends of roll 6, whereby the ends of roll 6 may be freely adjusted towards or from the roll 7 without binding of its bearings.

The stub shafts 8 at the upper ends of the respective rolls 6 and 7 carry belt pulleys 30 and 31; and in alignment with and above the belt pulleys 30, 31 is a take-up pulley 32 adjustably mounted on frame 1. At the base of frame 1 is journaled a shaft 33 having a pulley 34 (Fig. 1) disposed thereon in vertical alignment with the pulleys 30, 31 and 32; and an endless belt 35 runs around the pulleys 30, 31, and 32 and 34, the belt 35 passing over the pulley 30 of roll 6, and under the pulley 31 of roll 7, then up and over the adjusting pulley 32 and down and under the pulley 34 on the drive shaft 33, whereby when the shaft 33 is driven in the direction indicated by the arrow in Fig. 1, the rolls 6 and 7 will be rotated in opposite directions, their adjacent peripheries moving upwardly as shown by arrows, Fig. 4. The drive shaft 33 may be conveniently driven by a large pulley 36 disposed thereon around which a belt 37 from a suitable prime mover runs.

The vertical adjustment of sliding frame 12 imparts a greater or lesser inclination to the pair of rolls 6 and 7. The articles A (Fig. 4) to

be classified as to caliber or size travel between the revolving rolls 6 and 7 from the feeding end of the machine towards the discharge end. Some such articles require less inclination of the rolls than others, due to their smoothness of surface, but same may be caused to feed or move automatically in proper timed relation by proper inclination of the pair of rolls 6 and 7 effected by rotating the hand-wheel 14.

The two rolls 6 and 7 are spaced closer together at the upper or feeding end of the machine than at the lower or discharge end, and due to such angularity or spacing the articles to be classified or sorted, in their travel down the inclined rolls 6 and 7, will at some point or distance from the feeding end reach the proper spacing through which same will drop into one of the fourteen receiving pans 4a.

At the feeding end of the machine is a hopper 40 for the articles to be sorted or classified, said hopper contracting towards its lower end into a discharge spout 41. Preferably hopper 40 is supported upon the frame members 1 and 3 by posts 42 (Fig. 1) adjustably mounted in socket members 43 mounted upon the top of frame 1 and upon the rear upper horizontal frame rod 3, so that the hopper will be disposed above rolls 6 and 7 but at the rear of the machine.

Mounted on the discharge spout 41 of the hopper is a collar 44 (Fig. 4) having spider arms 45 provided with depending bolts 46 at their outer ends supporting a vibrating pan 47 inclined downwardly in a direction towards the rolls 6 and 7. Pan 47 has an apron 47a at its lower end directing the articles downwardly between the rolls 6 and 7. Upon the bolts 46 are springs 48 thereby permitting adjustment and vibration of pan 47. Below the vibrating pan 47 is a vibrator which causes the articles on pan 47 to feed in timed or proper sequence to and between the classifying rolls 6 and 7, the articles travelling down between the inclined rolls 6 and 7 into position where same can drop through into a receiving pan 4a. A feed control collar 50 is located on the collar 44 just above the vibrating pan 47, and may be adjusted vertically so as to control the feeding of the articles from the hopper 40 to the vibrating pan 47. Some articles will require less space between collar 50 and pan 47 than others for proper feeding, and the adjustment of collar 50 is therefore essential to prevent overloading of the vibrating pan 47 with articles so that same cannot be properly spread and fed to the rolls 6 and 7. Also the vibrating pan 47 is adjustable so that the proper angularity can be made to assist in the feeding operation by retarding the rolling movement of the articles sufficiently to prevent jamming thereof before entering between the rolls.

In the embodiment shown, an electric vibrator is used consisting of an electro-magnet 60 operated by alternating current to actuate a hammer 61 mounted on a spring and which contacts a fiber plate 62 attached to the bottom of the vibrating pan 47. However, if desired, any desired mechanical vibrator may be used.

When the machine is used to grade, sort, calibrate or separate armor piercing bullets for cartridges of specified caliber, the roll 6 is adjusted by means of the hand-wheels 21 and 26 to properly space rolls 6 from roll 7 to allow for the total tolerance, and the bullets of the specified caliber are placed in hopper 40, and the machine then operated to feed the bullets from

hopper 40, the same being fed in a positive and easily controlled manner by the vibration of pan 47 upon which the articles are properly spaced and fed. My machine will classify or sort approximately two hundred cores a minute with more accuracy than can be done by six ordinary operators using hand-gauges and hand-checking as to diameter. My machine may also be used for sorting or classifying ball bearing balls, wrist pins, or various other articles.

I do not limit my invention to the exact form shown in the drawings, for obviously changes may be made therein within the scope of the claims.

15 I claim:

1. A machine, comprising a frame; a second frame spaced therefrom; a sub-frame vertically movably mounted in the second frame; a pair of adjacent rolls of substantial length having their axes disposed in a common plane inclined downwardly with respect to the horizontal; said rolls having their ends journaled in bearings in the first frame and sub-frame respectively; means for rotating the rolls in opposite directions with their adjacent peripheries moving upwardly; means for adjusting the sub-frame in the second frame; said bearings being rotatable on horizontal axes whereby the sub-frame may be adjusted without binding of the bearings; means carried by the first frame and sub-frame for adjusting the spacing of the bearings at each end of the rolls to vary the clearance between the rolls in said common plane and to provide a greater clearance at the lower end than at the upper end of the rolls; means for feeding articles between the upper end of said rolls whereby same will progress downwardly therebetween; means for collecting at spaced increments along the length of the rolls the articles which drop therebetween during such progression; said bearing spacing adjusting means including movable yokes rotatable on horizontal axes and surrounding and spaced from the bearings and having opposed vertically disposed pivot pins entering the bearings whereby clearance may be adjusted without binding of the bearings; and means for moving said yokes.

2. A machine, comprising a pair of adjacent rolls of substantial length having their axes disposed in a common plane inclined downwardly with respect to the horizontal; a frame at the upper end of the rolls; a second frame at the lower end of the rolls; a sub-frame slidably mounted in the second frame; said rolls being journaled in bearings carried by the first frame and sub-frame; said bearings being rotatable on horizontal axes whereby the sub-frame may be shifted without binding of the bearings; means for shifting the sub-frame in the second frame; means for rotating the rolls in opposite directions with their adjacent peripheries moving upwardly; means for adjusting the clearance between the rolls in said common plane to provide a greater clearance at the lower end than at the upper end of the rolls; said clearance adjusting means including yokes surrounding and spaced from the movable bearings having opposed vertically disposed pivot pins entering the movable bearings, whereby the clearance may be adjusted without binding of the movable bearings; and means carried by the first frame and sub-frame respectively for shifting the said yokes.

ROBERT K. BARRY.
